UNITED STATES PATENT OFFICE

WARREN NOBLE, OF DETROIT, MICHIGAN, ASSIGNOR TO ELECTROMASTER, INC., OF DETROIT, MICHIGAN, A CORPORATION OF MICHIGAN

WALL PLUG AND RECEPTACLE

Application filed June 27, 1929. Serial No. 374,129.

This invention relates to electric wall boxes and has for its object to provide a wall box including a plug and a receptacle together with a suitable retainer therefor which may 5 be attached to a wall in order to eliminate the form of switch boxes which are used at present and which are rather large and unsightly and comparatively expensive to install. This plug being of the type to carry 10 a heavy current load, as, for instance, to an electric range will be understood to be of a very sturdy nature.

Another object of this invention is to provide a housing for the aforementioned wall box which will retain all the component parts of the receptacle in assembled position and acts as a complete housing for the said receptacle together with a substantial amount of the plug in order that the junction line between them may be well shrouded for general protective purposes.

A further object of the invention is to provide a device as described which will extend substantially longitudinally of the wall to 25 which it is attached in contradistinction to protruding outwardly at right angles to the wall, and to provide a suitable means as an integral feature of the device which will maintain the plug receiving end of the receptacle in spaced relation with the wall to a sufficient extent to forestall any damage to 30 the wall or to the plug by a scraping action upon insertion of the plug. In carrying this into effect, I prefer to construct the receptacle housing in two parts, one of the parts enclosing three sides of the receptacle body while the remaining side is open, lateral walls being provided with tapered recesses to give 35 a wedge shaped entrance for the base plate, the whole receptacle assembly being secured to the wall by screws extending therethrough.

Other objects and advantages such as ease and cheapness of manufacture, neatness and the like, will become hereinafter apparent as reference is had to the accompanying drawing wherein is illustrated, by way of example, a practical embodiment of my invention, and in which:

50 Figure 1 is a vertical section of the im-

proved wall box taken along the line 1^x—1^x of Figure 2;

Figure 2 is a vertical section taken along the line 2^x—2^x of Figure 1; and

Figure 3 is a transverse section taken on the line 3^x—3^x of Figure 2.

Similar characters of reference indicate similar parts in the several figures of the drawing.

1 indicates a wall or a similar surface which 60 may be vertical, inclined, or in any other plane, and to this wall is secured a receptacle housing 2 which is shown as being of a three sided construction with the open face against the wall and the open end uppermost, although it will be understood that the said 65 open end of the housing may face in any direction desired according to the requirement of the installation.

The margins of the lateral portions of the 70 housing are formed as at 3 to provide tapered recesses to receive a base plate 4 in the form of a wedge. The base plate is provided with orifices 5 suitably positioned to permit the screw 6, by which the housing 2 is secured to the wall, to pass therethrough and thereby lock the said base plate in position in the said housing.

The receptacle body comprises two preferably identical members 7, such as of porcelain, suitably recessed in their meeting faces 80 at 8 to receive contact members 9 and the ends of electric leads 10 together with the means, such as 11, securing the said leads to the inner ends of said contacts. These members 7 of the receptacle body have also orifices 12 therein through which the said screws 6 pass, thereby securing the said members against displacement within the housing. It 85 will be seen that the screws which secure the 90 housing to the wall, and the wedge plate 4 which is in turn secured into position by the said screws, together form a very simple and effective method of assembling and firmly locking the receptacle body within the housing.

The housing extends materially beyond both ends of a receptacle body to provide an enclosed chamber below the said body to receive the electric leads 10 and a shrouded por- 100

tion above the said body to receive a plug body.

This plug body also comprises two preferably identical members 13 recessed as at 13^a 5 to receive and retain therein prongs 14, corresponding to the contacts 9 of the receptacle body, and to receive the wires of a cable 15, the ends of which wires may be and preferably are soldered to the inner ends of said 10 prongs. The outer faces of the members 13 of the plug may be recessed as at 16 to receive links or plates 17 through which securing bolts 18 are passed to secure the two members of the plug body together.

15 The outer end of the said plug body is adapted to enter the shrouded portion of the receptacle housing 2 so that the junction between the plug body and the receptacle body is well within the said receptacle housing as 20 shown. This provides for protection of both the plug body and the receptacle body at this junction and also for the effective supporting of the plug body against lateral or rocking movement relative to the receptacle body, 25 with consequent minimizing of any possibility of accidental breakage or strain on the prongs or surrounding parts of the device; and it further affords a guide for the insertion of the plug into position.

30 The two members of the plug are preferably so proportioned that they clamp firmly upon the body of the cable 15 to prevent any tendency of the cable to be pulled from the body of the plug and thus strain the connection between the cable wires and the prongs. 35 Similarly it is preferred that the two members of the receptacle body exert a clamping upon the insulation of the electric leads 10, although this is not so important as in actual 40 use the receptacle body is a stationary member.

It will be noted that the general plane of the plug and receptacle is inclined to the plane of contact between the receptacle housing and the wall, which is desirable to permit 45 more ready application of the plug to the receptacle and to prevent scraping between the plug and the wall when the plug is inserted and removed. This inclination at the same 50 time provides the necessary spacing between the receptacle body and the wall to admit of the insertion of the wedge-shaped base plate 4.

The device as described is very simple and 55 easy to manufacture, assemble and install, and provides a cheap and effective means of affording connection for electric stoves and similar devices in houses without necessitating the usual types of outlet boxes, receptacles, and plugs together with incidental expense which has heretofore usually been called for.

This invention may be developed within 60 the scope of the following claims without departing from the essential features of the

said invention, and it is so desired that the specification and drawing be read as being merely illustrative, and not in a limited sense, except as necessitated by the prior art.

What I claim is:

1. In a device of the class described, a substantially flat receptacle having openings in one of its faces for receiving the contact members of a plug, means in said openings for making electrical connection with said members, a housing for said receptacle having side walls extending beyond said receptacle, and a base plate insertable between the extended portions of said side walls, said side walls being shaped to receive and hold said base plate. 70

2. In a device of the class described, a substantially flat receptacle having openings in one of its faces for receiving the contact members of a plug, means in said openings for making electrical connection with said members, a housing for said receptacle having side walls extending beyond said receptacle, a base plate insertable between the extended portions of said side walls, said side walls being shaped to receive and hold said base plate, and means passing through said housing and said base plate to maintain said base plate in position. 85

3. In a device of the class described, a substantially flat receptacle having openings in one of its faces for receiving the contact members of a plug, means in said openings for making electrical connection with said members, a housing for said receptacle having side walls extending beyond said receptacle, a base plate insertable between the extended portions of said side walls, said side walls being shaped to receive and hold said base plate, and means passing through said housing, said receptacle and said base plate to maintain said receptacle and said base plate in position relative to said housing. 95

4. In combination, a plug, a receptacle, a housing for said receptacle, said housing extending materially around said receptacle and overhanging the receiving edge thereof to partially cover said plug, said housing terminating in angularly projecting sides having inturned flanges at the extremities thereof, a wedge shaped base plate insertable between said flanges and said receptacle to maintain said receptacle and said housing in assembled relation, and a screw extending transversely through said housing, said receptacle and said base plate to lock them in fixed relation and to angularly attach said socket to a support. 110

5. In an electrical wall-fitting adapted to 1 have inserted therein an electrical plug, wedge means insertable between the fitting and a wall to which the fitting may be attached for causing said fitting to be inclined outwardly with its plug receiving end outer- 12

most to facilitate insertion of the plug therein.

6. In an electrical wall-fitting adapted to have inserted therein an electrical plug, 5 wedge means insertable between the fitting and a wall to which the fitting may be attached for causing said fitting to be inclined outwardly with its plug receiving end outermost to facilitate insertion of the plug there- 10 in, and transverse fastening means formed to be projected thru the fitting and said wedge means into the wall for securing the fitting to the wall and for holding the wedge means in proper position with respect to the 15 wall and fitting.

7. As an article of manufacture, a wall receptacle formed to receive an electrical plug comprising a housing having its base portion formed to define a wedge-shaped pocket, elec- 20 trical contact means in said housing and a wedge-shaped baseplate disposed in said pocket for causing said housing to be inclined from the wall to which it is attached to facilitate insertion of a plug therein for coopera- 25 tion with said contact means.

In testimony whereof I affix my signature.
WARREN NOBLE.
